UNITED STATES PATENT OFFICE.

SOLA B. DUNN, OF CHICAGO, ILLINOIS.

VETERINARY INSTRUMENT.

1,149,562.

Specification of Letters Patent.

Patented Aug. 10, 1915.

Application filed July 26, 1913. Serial No. 781,343.

To all whom it may concern: Be it known that I, SOLA B. DUNN, a citizen of the United States, residing at Chicago, in the county of Cook and State of Illinois, have invented certain new and useful Improvements in Veterinary Instruments, of which the following is a specification.

My invention relates in general to veterinary instruments and more particularly to emasculators.

In order to prevent hemorrhages, the jaws of emasculators have heretofore been provided adjacent their cutting edges with co-operating crushing surfaces to lacerate the spermatic cord and thereby close the severed end thereof. Emasculators so constructed do not, however, always prevent hemorrhages, especially in the case of full grown animals, as the pressure of the blood is sufficient to open the crushed portion of the spermatic cord.

The primary object of my invention is to provide an emasculator which will not only crush the spermatic cord adjacent its severed end, but will compress the same immediately above the crushed portion so as to restrict the flow of blood and prevent the pressure thereof from opening the crushed portion of the cord before it is permanently closed by healing.

Another object of my invention is to provide an improved emasculator having means for compressing the spermatic cord adjacent the severed and crushed end thereof to an extent sufficient to restrict the flow of blood but insufficient to lacerate the cord.

My invention will be more fully disclosed hereinafter with reference to the accompanying drawing in which the same is illustrated as embodied in a convenient and practical form and in which:

Figure 1 is a perspective view; Fig. 2, a cross-sectional view through the jaws in the position they assume immediately after severing the cord; Fig. 3, a perspective view of the jaws looking toward the opposite side from that shown in Fig. 1; Fig. 4, a perspective view of one of the jaws showing a modification.

The same reference characters are used to designate the same parts in the several figures of the drawing.

Reference letters A and B designate levers which are crossed and pivotally connected at their point of intersection by any suitable

device, such for instance, as a thumb screw, a. The short arms of the levers consist of jaws A' and B', while the longer arms of the levers serve as handles to oscillate the levers and thereby relatively move the jaws. The jaw A' is provided with a longitudinal central opening b through which the jaw B' is adapted to be oscillated. The jaw A' at one side of the opening there through is provided with a cutting edge a' with which co-operates a cutting edge b' on the opposite jaw B'.

The jaw A' at the opposite side of the opening b from the cutting edge a', is provided with transverse serrations which form a crushing shoulder a². The adjacent edge of the jaw B' is also provided with transverse serrations which form a crushing surface B² which co-operates with the crushing surface a².

The jaw A' is provided with a laterally projecting shoulder a³ in a plane above the crushing surface a², which is provided with longitudinal serrations. The jaw B' is provided with a yielding block D which occupies a position to aline with the shoulder a³ when the jaws are moved together, as shown in Fig. 2. Any suitable means may be provided for yieldingly supporting the block D upon the jaw B' such, for instance, as screws d' and d² extending through elongated slots in the ends of the block D, and engaging screw threaded holes in the jaw B'. The block D, is engaged by the ends of a leaf spring E which is secured intermediate of its ends to the jaw B' by means of a screw e. The tension of the spring normally retains block D in position shown in Figs. 1 and 2 relatively to the jaw B'.

In Fig. 4 I have shown a modified means for yieldingly supporting the block D upon the jaw B'. In this modification pins or screws d³ and d⁴ are carried by the ends of the block D and extend through slots formed in the jaw B'. A leaf spring E' is secured by a screw e' to the jaw B' and is provided with bent ends e³ and e⁴ which extend into the slots in jaw B' and engage the screws d³ and d⁴.

In order to vary the degree to which the jaws may be closed, an adjustable set screw F extends through one of the levers adjacent the point of pivotal connection of the levers so as to engage the opposing lever and thereby limit their movement toward each other.

The manner of using and operation of my

improved emasculator are as follows: The jaws A' and B' are placed around the cord which is to be severed, and pressure is applied to the levers A and B so as to move the jaws toward each other. The movement of the jaws toward each other causes the co-operating serrated crushing surfaces a^2 and b^2 to crush and lacerate the interposed portion c^2 of the cord, while a further movement of the jaws together causes the co-operating cutting edges a' and b' to sever the cord, as shown in Fig. 2. A further movement of the jaws toward each other causes the pressure block D to yieldingly compress the portion c^3 of the cord between the longitudinal serrations on said block and the serrations on the opposing surface of the shoulder a^3 . The pressure exerted upon the portion c^3 of the cord is limited by tension of the spring E, so that only a sufficient pressure is exerted upon the cord by block D to compress the same without crushing or lacerating it.

From the foregoing description it will be observed that I have invented an improved emasculator in which the cord will be crushed and lacerated at a point adjacent the severed end of the cord, and in which the cord above the lacerated portion thereof, will be compressed so as to restrict the flow of blood thereto and thereby protect the crushed portion of the cord from the pressure of the blood which would tend to open the crushed portion and produce a hemorrhage.

It will be further observed that in my improved emasculator only a sufficient pressure is exerted upon the cord above the crushed portion thereof to restrict the flow of blood without crushing or lacerating same.

While I have described more or less in detail the specific form in which I have illustrated my invention as embodied, yet I do not wish to be understood as limiting myself thereto, as I contemplate changes in form, proportion of parts, and substitution of equivalents, as circumstances may require or as may be deemed expedient.

50 I claim:

1. An emasculator comprising relatively movable jaws having co-operating cutting edges and relatively yielding compressing surfaces spaced apart from the cutting edges, and means limiting the compressing movement of the compressing surfaces.

2. An emasculator comprising relatively

movable jaws having co-operating cutting edges and crushing surfaces, and also having relatively yielding compression surfaces 60 spaced apart from the crushing surfaces.

3. An emasculator comprising relatively movable jaws having co-operating cutting edges, one of said jaws having a laterally projecting shoulder, a pressure block yieldingly supported upon the other jaw in position to co-operate with said shoulder in exerting a limited pressure, and adjustable means for varying the limit of pressure between the block and shoulder. 70

4. An emasculator comprising relatively movable jaws having co-operating cutting edges, one of said jaws having a laterally projecting shoulder, a pressure block yieldingly supported upon the other jaw in position to co-operate with said shoulder, a spring secured to said second jaw and bearing upon said block to resist the yielding thereof, and means for limiting the movement of said pressure block toward said shoulder. 75

5. An emasculator comprising relatively movable jaws one of which has a longitudinal slot through which the other reciprocates, said jaws having co-operating cutting edges at one side of said slot, a laterally projecting shoulder on said first jaw on the opposite side of said slot from the cutting edge, and a bodily movable pressure block yieldingly supported upon the second jaw 90 in position to co-operate with said shoulder in exerting a yielding pressure after said cutting edges have passed each other into overlapped position.

6. An emasculator comprising relatively movable jaws one of which has a slot through which the other reciprocates, the said jaws having co-operating cutting edges at one side of said slot and co-operating crushing surfaces at the other side of said slot, a laterally projecting shoulder on said first jaw spaced apart from the crushing surface thereof, and a pressure block yieldingly supported upon said second jaw above the crushing surface thereof to engage said shoulder after said crushing surfaces have passed each other into overlapped position. 95

In testimony whereof, I have subscribed my name.

SOLA B. DUNN.
